UNITED STATES PATENT OFFICE.

JOSEPH L. DONAT, OF CHICAGO, ILLINOIS.

HEATING DEVICE.

Application filed February 15, 1923. Serial No. 619,110.

To all whom it may concern:

Be it known that I, JOSEPH L. DONAT, a citizen of the United States, and a resident of the city of Chicago, in the county of Cook and State of Illinois, have invented certain new and useful Improvements in a Heating Device; and I do hereby declare that the following is a full, clear, and exact description of the same, reference being had to the accompanying drawings, and to the numerals of reference marked thereon, which form a part of this specification.

This invention relates to heating devices more particularly for household purposes.

It frequently happens that one or more of the rooms in a house are insufficiently heated. Moreover, it is often the case that a chimney is located in one of the walls of such a room up which a large amount of heat escapes.

One of the principal objects of the present invention is to provide means for utilizing a part of this heat which now goes to waste for heating the air in a room.

A further object of the invention is to provide an improved form of radiator.

Another object of the invention is to provide means for varying the amount of heat transmitted from the chimney gases to the room.

An additional object is to provide means for minimizing the deposit of soot in the radiator and means for cleaning the radiator when desired.

Other and further important objects of this invention will be apparent from the disclosures in the specification and drawings.

On the drawings:

Figure 1 is a vertical section through a chimney provided with a radiator constructed in accordance with the present invention.

Figure 2 is a section on the line 2—2 of Figure 1.

Figure 3 is a front elevation of the radiator.

As shown on the drawings:

The chimney flue 10 is surrounded by the usual brickwork 11. An aperture 12 is formed in this brick-work on the room side of the chimney and around its periphery is arranged an iron frame 13. This frame not only holds the brick-work in place but also provides means for supporting the radiator 14. The outer edge of the frame 13 is formed with an outwardly extending flange 13^b having a rearwardly formed portion 13^c

thereon affording an insulating chamber 13^e which prevents undue transmission of heat to the plaster or other chimney covering. For this purpose the frame extends outwardly to form a bearing surface flush with the wall of the room. On the upper portion of this bearing surface is arranged an upwardly turned lip 15 adapted to engage a downwardly extending lip 16 on the upper edge of the radiator. The lower part of the radiator is clamped to the frame 13 by a screw 17. Laterally the radiator is held in position by means of ribs 18.

Across the center of the aperture on the chimney side is arranged a plate 19 forming a part of the frame 13. This plate serves as a support for a rod 20 on which a damper 21 is arranged. This rod extends through the radiator 14 and is provided at its outer end with a detachable handle 22. By turning the damper the flow of hot gases over the surface of the radiator may be varied.

The radiator itself may conveniently consist of a cast-iron box formed on the front side with a series of deep vertical corrugations 23 extending into the aperture 12. By this means a large heat transmitting surface is obtained.

On the corrugations 23 are formed a series of horizontal ribs 24 which aid in preventing undue accumulation of soot on the corrugations. Such soot as may accumulate may readily be removed by detaching the radiator. This is a simple operation involving merely the removal of the damper handle 22 and the screw 17 when the radiator may be lifted off the lip 15 on which it hangs.

Around the radiator is a grid 25 which prevents a person from accidentally coming in contact with the highly heated surface of the radiator box.

I am aware that numerous details of construction and operation may be varied through a wide range without departing from the principles of this invention, and I therefore do not purpose limiting the patent granted hereon otherwise than as necessitated by the prior art.

I claim as my invention:

1. A heating device comprising a chimney having an aperture therein leading to a room, a radiator arranged in said aperture having one wall substantially flush with the front wall of the chimney, a damper in the chimney behind the radiator, said wall being apertured above and below said damper

to allow chimney gases to by-pass around said damper when the latter is closed.

2. A heating device comprising a chimney having an aperture therein leading to a room, a radiator arranged in said aperture having a front heat transmitting wall, and a rear wall adapted to act as a portion of the front wall of the chimney, and a damper behind said rear wall adapted when closed to force the chimney gases to pass in front of said rear wall, the latter being apertured above and below said damper to allow of such passage of said gases.

3. A heating device comprising a chimney, a damper in the chimney, a by-pass

around said damper, a metal wall for said by-pass having deep vertical corrugations, and a series of horizontal ribs thereon.

4. A heating device comprising a chimney having an aperture therein, a casing within said aperture having top, bottom, side and rear walls, the rear wall being apertured top and bottom for the passage of chimney gases, a damper behind said rear wall and a detachable front wall having inwardly extending corrugations formed therein.

In testimony whereof I have hereunto subscribed my name.

JOSEPH L. DONAT.
